DESIGN FOR CARPET.

SPECIFICATION forming part of Design No. 23,486, dated July 24, 1894.

Application filed June 28, 1894. Serial No. 516,021. Term of patent 3½ years.

To all whom it may concern:

Be it known that I, WILLIAM F. BROWN, a subject of the Queen of Great Britain, residing at Newark, in the county of Essex and State of New Jersey, United States of America, have invented and produced a new and original Design for a Carpet, of which the following is a specification, reference being had to the accompanying drawing, forming a part thereof, which represents a face view of a carpet in which the new design is embodied.

The invention relates to a design to be worked into or upon surfaces such as carpets and similar fabrics, and it consists in the novel configuration of figures, as herein shown and claimed.

The design consists of a body A and a border B. The body A is decorated with groups of floral figures, each group comprising curved bi-secting sprays of small flowers, a ribbon tie

and conventional foliation, rosette figures being disposed between the floral groups. The border B consists of a horse-shoe spray of small flowers tied with a bow, alternating with floral figures conforming to those described with reference to the decoration of the body. Rosette figures are arranged with dado effect at the outer edge of the border. 25

I claim—

1. In a design for a carpet, the body A, substantially as shown. 30
2. In a design for a carpet, the border B, substantially as shown.
3. The design for carpets, consisting of the body A and the border B, substantially as 35 shown.

WILLIAM F. BROWN.
